UNITED STATES PATENT OFFICE.

JOSEPH BOEING, OF JOHNSTOWN, PENNSYLVANIA.

REGISTRATION

3-242-19726

Specification of Letters Patent.

Patented June 1, 1915.

Application filed February 20, 1915. Serial No. 3,681.

To all whom it may concern:

Be it known that I, JOSEPH BOZIC, a citizen of the United States, residing at Johnstown, in the county of Cambria and State of Pennsylvania, have invented certain new and useful Improvements in Registers, of which the following is a specification, reference being had to the accompanying drawings.

This invention relates to certain improvements in registers and has relation more particularly to a device of this general character especially designed and adapted for use in connection with check controlled apparatus; and an object of the invention is to provide a register including novel and improved means whereby the same is operated under the influence of a check whereby an accurate record may be kept relative to the aggregate of the checks which may be employed.

Furthermore, it is an object of the invention to provide a register of this general character adapted to be employed in connection with a check controlled apparatus including a chute or conduit intersected by an operating member for the register adapted to be engaged by a check whereby said register is operated.

The invention consists in the details of construction and in the combination and arrangement of the several parts of my improved register whereby certain important advantages are obtained and the device is rendered simpler, less expensive and otherwise more convenient and advantageous for use, all as will be hereinafter more fully set forth.

The novel features of the invention will be apparent from the appended claim.

The other day my invention may be the better understood, I will now proceed to describe the same with reference to the accompanying drawings, wherein—

FIGURE 1 is a view in elevation of a register constructed in accordance with my invention, and in upright position. The eccentric portion of the check controlled apparatus being indicated partly in section and partly in elevation; FIG. 2 is an enlarged view in elevation of my improved register with a base plate removed; FIG. 3 is a view in elevation opposite to that shown in FIG. 1; and FIG. 4 is a view, partly in top plan and partly in section, of my improved register as a single set article.

As disclosed in the accompanying drawings, A denotes a portion of a cabinet of a check controlled apparatus and C denotes a chute or conduit into which the check for controlling the operation of the apparatus is adapted to be deposited, said chute being so disposed as to permit the check to pass therethrough by gravity. As the construction and operation of the apparatus itself 60 form no part of my invention, it is not thought that a detailed description thereof is necessary.

Suitably supported, as at 1, within the cabinet A and in close proximity to the chute 70 or conduit C is my improved register R comprising a casing 8 having rotatably mounted therein upon parallel axes, the disks 3, herein disclosed as three in number, having their peripheral portions disposed in overlying relation and such peripheral portions are further provided with the teeth 4, herein disclosed, in each instance, as ten in number, and each of said disks immediately adjacent the teeth is provided with an annular series of identifications 5, herein arranged in sequence from "0" to "9". Certain of said disks are provided with the lateral pins or projections 6 adapted to coact with the teeth 4 of the next adjacent disk 1, in a manner and for a purpose which is believed to be self-evident. The peripheral portion of one of the end disks 3 projects beyond the adjacent extremity of the casing 8 and the teeth 4 thereof are adapted to be engaged by the gravity pawl 7 pivotally secured to the upstanding arm 3 carried by the longitudinally disposed lever 9 pivotally engaged intermediate its length, as at 10, with the casing 8 adjacent the outer face thereof and whereby it will be perceived that upon downward movement being imparted to the outer extremity of the lever 9, the disk 3 with which the dog or pawl 7 engages will be caused to move a distance equal to the width of the outer edge of the casing 8.

one tool. The lever 9 is normally maintained in a horizontal position and, as herein disclosed, such normal position is maintained under the influence of the retractable member 11, herein disclosed as a conventional coil spring, having one extremity secured to the lever 9 and its opposite extremity pivotally attached to the casing 8. In order to facilitate the return of the lever 9 under the influence of the spring 11, it is to be foreseen to be of advantage to move the lower extremity of the lever 9 out

larged, as at 12, to afford a counter balance and operating in a manner and for a purpose which is believed to be self-evident.

Below the intermediate disk 3, as herein set forth, the casing 2 is provided with the inwardly directed post 14 to which are anchored the inner extremities of the flat springs 15, the opposite extremities of said springs 15 contacting with the peripheries 10 of the disks 3 to normally maintain the same against rotation.

The outer extremity of the lever 9 is adapted to intersect the chute or conduit C and as is particularly shown in Fig. 1 of the accompanying drawings, said chute C is provided with an elongated longitudinally disposed slot 16 through which the outer extremity of said lever 9 projects, and said portion of the lever 9 within the chute or conduit C is adapted to be engaged by the check as it passes through the chute or conduit, such engagement resulting in sufficient downward movement of the lever 9 as to result in the requisite operation of the register. 20 In order that no obstruction may be afforded by the lever 9 to prevent the check from continuing through the chute or conduit C after the lever 9 has been depressed, it is to be observed that the wall of the conduit opposite to the slot 16 is offset or enlarged transversely as indicated at 17.

In order to limit the upward movement of the lever 9 under the influence of the spring 11 and the weighted portion 12, I provide 35 the outer face of the casing 2 with the lug or projection 18 positioned above the lever 9 and with which said lever is adapted to contact, as is believed to be clearly shown in Fig. 8.

40 Coating with the casing 2 is the removable face plate 19 having produced therein

suitable openings 20 through which the identities 5 upon the disks 3 are adapted to be exposed and whereby a convenient reading of the register may be had.

45 In practice, I find it of advantage to have the cabinet A in close proximity to the register R provided with a door D to provide a means whereby access to the register may be had with convenience.

50 From the foregoing description, it is thought to be obvious that a register constructed in accordance with my invention is of an extremely simple and comparatively inexpensive nature and is particularly well 55 adapted for use by reason of the convenience and facility with which it may be assembled, and it will also be obvious that my invention is susceptible of some change and modification without material departure 60 from the principles and spirit thereof and for this reason I do not wish to be understood as limiting myself to the precise arrangement and formation of the several parts herein shown in carrying out my invention in practice.

65 I claim:

In combination with a check controlled apparatus including a chute, a register comprising an operating member movable under 70 the influence of a check, said chute being provided in one of its faces with a suitable opening through which the movable operating member of the register is directed, the opposite face of the chute adjacent the opening being offset outwardly.

75 In testimony whereof I hereunto affix my signature in the presence of two witnesses.

JOSEPH BOZIC.
